UNITED STATES PATENT OFFICE.

WILHELM HEEPE, OF WILHELMHAVEN, GERMANY, ASSIGNOR TO ACHILLE STARACE & CO., OF NEW YORK, N. Y., A CORPORATION OF NEW YORK.

SAFETY-RAZOR-BLADE STROPPER.

1,405,032.

Specification of Letters Patent. Patented Jan. 31, 1922.

Application filed April 3, 1920. Serial No. 371,343.

To all whom it may concern:

Be it known that I, WILHELM HEEPE, a citizen of the Republic of Germany, residing at Wilhelmshaven, Germany, have invented 5 an Improvement in Safety-Razor-Blade Stroppers, of which the following is a specification.

This invention relates to an apparatus for sharpening or stropping safety razor blades 10 of the thin sheet metal type, provided with either one or two cutting edges, and has particular reference to a device of this character whereby the sharpening element is bodily revolved, by a swinging action, about the 15 axis of the razor blade holder, and at the same time said sharpening element is itself rotated about its own axis, means being provided for rotating said sharpening element during its bodily gyratory movement, and 20 means being also provided for maintaining the razor blade in engagement with said sharpening element at all times during the operation of the device.

The particular object of the invention is 25 the provision of a device of the character indicated, which may be held in the hand by a supporting spindle, preferably in a vertical position, and revolved or gyrated about the axis of said spindle to perform the 30 sharpening operation, said operation being possible owing to the particular design and construction of the cooperating parts and the peculiar relation thereof to the novel means of operating said device.

35 Another object of the invention is to so construct and shape the sharpening element that the same will traverse up and down the edge of the blade during the combined rotation and gyration, of said element, there- 40 by producing an even and uniform stropp- ing or sharpening of the edge.

A further object is to so mount the razor blade holder that the razor blade will be held constantly in contact with the sharpening element, irrespective of the direction in 45 which the device is revolved or swung about its supporting spindle.

It is also contemplated to provide means 50 for removing or replacing the contacting surface of the sharpening element according to the character of the sharpening desired.

Briefly, the invention comprises a main 55 supporting spindle, having mounted about its intermediate portion and at right angles thereto, the inner end of a swinging or re-

volving arm, the outer end of said arm having journalled therein, in a vertical position, a rotatable support carrying a detachable sharpening element. The upper end portion of the spindle projecting above the 60 inner end of the swinging arm forms a support for the razor blade holder, said holder being frictionally held by suitable means against free rotation about said spindle. The vertically disposed support for the 65 sharpening element is arranged parallel to the upper end of the spindle and so spaced therefrom as to permit the blade carried in the blade holder, supported by said spindle, to properly engage the sharpening element 70 and be carried around with it, as said sharpening element, moving with the swinging arm, is revolved about the spindle during the operation of the device. The lower end portion of the spindle, below the swinging arm, is provided with a hand grip forming a means for operating the device in the manner specified.

To provide for a rotation of the sharpening element about its own axis, during the 80 bodily gyratory movement thereof about the supporting main spindle, said spindle and supporting axis of the sharpening element are provided with suitable connecting gearing or similar operating means, mounted 85 within the swinging arm in a manner to be hereinafter more fully described.

In the accompanying drawings:—

Fig. 1 is an elevation of the safety razor blade stopper made in accordance with the 90 present invention.

Fig. 2 is a view, partly in elevation and partly in section, of said device.

Fig. 3 is a bottom plan view of the swinging arm with the gear cover removed. 95

Fig. 4 is a top plan view of the device.

Fig. 5 is a cross-section on lines A—B of Fig. 1.

Figs. 6 and 7 are plan views of the gripper members adapted to be attached to the 100 holder for securing the razor blade in position, and

Fig. 8 is an elevation of a modified form of the invention.

Referring to the drawings in detail, the 105 apparatus comprises a substantially vertical main supporting spindle 2, the lower end portion of which being supplied with a hand grip 1, and the upper end portion with a safety razor blade holder comprising com- 110

plementary clamping plates 3 and 4, between the outer ends of which the blade 5 is supported and clamped. The inner end portions of said plates 3 and 4 are crossed about the 5 upper end portion of the spindle 2, and said plates in their clamped position are held by a spring 6 encircling the said spindle 2 said spring having its free ends engaging the inner faces of the crossed end portions of the 10 plates 3 and 4.

Mounted about the intermediate portion of the spindle 2, between the hand grip 1 and blade holder, and at right angles thereto, is a swinging or revolving arm 18, said 15 arm being preferably provided with a weighted outer end 24. The inner end of said arm surrounding the spindle 2 is also provided with an enlargement 25, forming a proper bearing for this supported end of 20 the arm. Mounted in the weighted end 24 of the swinging arm 18 is a rotatable spindle 16, having detachably secured thereto a support 8 for a grinding or stropping element 7, removably secured to said support 8. 25 This support 8 is preferably in the form of an oblique, transverse section of a cylinder, the upper face thereof being hollowed out as at 10, and a portion of the outer periphery recessed, producing a peripheral flange 9, and thereby providing a means for seating or supporting the sharpening element 7. In order to securely clamp the sharpening element 7 to its support 8, there is positioned within the hollow portion 10 a 30 spring 11, comprising a single coil 12, provided with a pair of laterally projecting U-shaped clips or members 14, adapted to extend into laterally disposed slots 15 in the walls of the support 8 formed by the hollowed out portion 10, and by reason of their 35 spring action bear against and engage the corresponding interior surfaces of the grinding or stropping element 7, whereby the latter is held in the desired position on said 40 support, yet at the same time can be readily removed when necessary to substitute a different character of strop or sharpening element. For ordinary stropping operations, the element 7 will be constructed of leather 45 or the like, but when it is desired to produce a grinding action rather than a stropping action, said leather element can be removed and a grinding element substituted therefor.

In order to maintain the razor blade in 50 position between the clamping plates 3 and 4, there is employed a form of gripper shown in Figs. 6 and 7. This preferably comprises a strip of suitable material 26, provided on one surface with pins 27 adapted to fit into corresponding recesses in the 55 clamping plate 3, and also with recesses 28 forming bosses on the reverse side of the gripper to enter the holes or openings ordinarily employed in the usual form of safety 60 razor blade, these openings in the razor

blade being indicated at 29. The gripper is also provided with a stem 30, adapted to pass through an opening formed in the clamping plate 3 for this purpose, and exteriorly of said clamping plate the stem 30 70 is supplied with a washer 31 for securing the gripper in position in the clamping plate 3. The stem 30 or the washer 31 may be manipulated with the handle 32, by means of which, as will be understood, the gripper 75 may be turned about the stem 30 as an axis so as to rotate the razor blade through an angle of 180° without removing the same from the holder of the apparatus, the parts of the holder being maintained in position 80 with the razor blade between them by the action of the spring 6. This spring 6 is secured in position in a groove 33 in the spindle 2, and, as will be apparent, normally maintains the parts of the holder together with the razor blade therebetween and frictionally binds said holder to said spindle.

The blade holder, as will also be understood, can be rotated about the spindle 2, 90 but because of the frictional action of the spring 6, it is so retarded in its movements as to lag behind the turning movement of the swinging arm 18, so that the edge of the strop is maintained against the edge 95 of the blade without the aid of special devices for accomplishing this purpose.

In the form of the invention shown in Fig. 8, the holding device for the blade is of a modified form and the gripper member 100 is omitted entirely. In this construction, one of the clamping plates of the blade holder is provided with knobs 34 and the other clamping plate with openings 35 in registering positions, so that the knobs 34 105 may pass through the fastening holes 29 in the razor blade and in the openings 35 to secure the blade in position in the holder.

The swinging arm 18 during the operation of the device is adapted to be revolved about the supporting spindle 2, and during this swinging movement the sharpening element 7 and the support 8 are carried therewith. At the same time this sharpening element is also caused to rotate about its own axis so 115 that said sharpening element is not only bodily revolved about the main supporting axis of the device but is also mounted for independent rotation. This is accomplished preferably by a train of gears consisting of 120 a gear 19 secured to the sharpening element supporting spindle 16, and a gear 22 secured to the main supporting spindle 2. Interposed between the gears 19 and 22 is an idler gear 20, mounted upon a stub shaft 21, 125 carried by the revolving arm 18. All of the above mentioned gears are housed within the hollowed portion 17 formed in the bottom face of said revolving arm 18, and said gears when in position are completely inclosed 130

within the arm 18 by a cover plate 23, as clearly shown in Fig. 2. With this construction, it will be noted that as the main supporting spindle 2 and its associated gear 22 are substantially non-rotatable during the operation of the device, the revolving action of the swinging arm 18 about said spindle will cause a rotation of the support 8, by reason of the interconnecting gears 19 and 20, in an obvious manner, as will be apparent upon referring to Fig. 2. During this operation the sharpening element 7 will be in contact with the edge of the razor blade as the support 8 is properly spaced with respect 10 to the razor blade and holder to permit this action. During the individual rotation of the sharpening element 7 and its bodily gyroscopic movement about the main supporting spindle 2, the razor blade will be pressed against the sharpening element 7, and at the same time the razor blade holder will be revolved about the spindle 2, the frictional engagement of the holder with the spindle maintaining the razor blade in contact with 20 the stropping element 7 at all times, irrespective of the direction in which the swinging arm 18 is revolving. During this sharpening operation, by reason of the peculiar shape of the sharpening element 7 and its support 8, said sharpening element will be caused to move up and down the same side of the razor blade during the continuous revolving of the arm 18 and the simultaneous individual rotation of the sharpening 30 element 7 in the same direction.

The whole operation, as above described, is performed by simply grasping the device by the hand grip 1, holding the same preferably in a vertical position, and executing a 40 swinging motion sufficient to cause the swinging arm 18 to revolve or gyrate about the main supporting spindle 2. Swinging the arm in one direction will sharpen one side edge of the razor blade, and in order to 45 sharpen the other side edge it is only necessary to reverse the swinging action. The arm 18, being provided with an enlarged weighted outer end portion 24, sufficient inertia is assured, which is necessary in order to produce 50 an efficient operation of the device in the manner specified.

What I claim is:

1. In a razor blade sharpening device, the combination with a supporting spindle, of a 55 swinging arm having its inner end revolvably mounted on said spindle, a razor blade holder frictionally carried by the upper end of said spindle above said arm, a rotatable sharpening element journaled in the outer end of said arm in a position to engage the razor blade carried by said holder, and means connecting the supporting journal of 60 said sharpening element and spindle, whereby the sharpening element will be individually rotated about its axis and simultaneously rotated about its axis and simultane-

ously revolved about the spindle, and the blade holder will be rotated around said spindle upon the swinging of the arm about the spindle.

2. In a razor blade sharpening device, the combination with a supporting spindle, of a swinging arm provided with an enlarged weighted outer end portion and having its inner end revolvably mounted on said spindle, a razor blade holder frictionally carried by the upper end of said spindle above said arm, a rotatable sharpening element journaled in the enlarged outer end of said arm in a position to engage the razor blade carried by said holder, and means also carried by said arm for connecting the supporting journal of the sharpening element and spindle, whereby the sharpening element will be individually rotated about its axis and simultaneously revolved about the spindle, and the blade holder will be rotated around said spindle upon the swinging of the arm about the spindle.

3. In a razor blade sharpening device, the combination with a supporting spindle, of a swinging arm provided with an enlarged weighted outer end portion and having its inner end revolvably mounted on said spindle, a razor blade holder frictionally supported upon the upper end of said spindle above said arm, a rotatable sharpening element in the form of an oblique, transverse, cylindrical section journaled in the enlarged outer end of said arm in a position to engage the razor blade carried by said holder, and means also carried by said arm for connecting the supporting journal of the sharpening element and spindle, whereby the sharpening element will be individually rotated about its axis and simultaneously revolved about the spindle and the blade holder will be rotated around said spindle upon the swinging of the arm about the spindle.

4. In a razor blade sharpening device, the combination with a supporting spindle, of a swinging arm provided with an enlarged weighted outer end portion and having its inner end revolvably mounted on said spindle, a razor blade holder frictionally supported upon the upper end of said spindle above said arm, a handle on the lower end of said spindle below said arm, a rotatable sharpening element in the form of an oblique, transverse, cylindrical section journaled in the enlarged outer end of said arm in a position to engage the razor blade carried by said holder, and means inclosed within the arm for connecting the supporting journal of said sharpening element and spindle, whereby the sharpening element will be individually rotated about its axis and simultaneously revolved about the spindle, and the blade holder will be rotated around said spindle, the razor blade being maintained in engagement with said sharpening element.

upon the swinging of the arm about the spindle.

5. In a razor blade sharpening device, the combination with a supporting spindle, of a 5 swinging arm having its inner end revolvably mounted on said spindle, a razor blade holder frictionally carried by the upper end of said spindle above said arm, a rotatable support for receiving a sharpening element 10 journalled in the outer end of said arm in a position to have said sharpening element engage the razor blade carried by said holder, means for detachably securing said sharpening element to said support, and means connecting the supporting journal of said sharpening element and spindle, whereby the sharpening element will be individually rotated about its axis and simultaneously revolved about the spindle and the blade holder 15 20 will be rotated around said spindle upon the swinging of the arm about the spindle.

6. In a razor blade sharpening device, the combination with a supporting spindle, of a swinging arm provided with an enlarged 25 weighted outer end portion and having its

inner end revolvably mounted on said spindle, a razor blade holder frictionally supported upon the outer end of said spindle above said arm, a hollow rotatable support for receiving a sharpening element in the 30 form of an oblique, transverse, cylindrical section, journalled in the enlarged outer end of said arm in a position to have said sharpening element engage the razor blade carried by said holder, a spring clip positioned with- 35 in the walls of said hollow support, the ends of said clip adapted to project through openings in said walls and engage the sharpening element for detachably securing said sharpening element to said support, and 40 means also carried by said arm for connecting the supporting journal of the sharpening element and spindle, whereby the sharpening element will be individually rotated about its axis and simultaneously revolved 45 about the spindle and the blade holder will be rotated around said spindle upon the swinging of the arm about the spindle.

Signed by me this 19th day of April, 1920.
WILHELM HEEPE.
